UNITED STATES PATENT OFFICE.

HARRY E. ASBURY, OF PHILADELPHIA, PENNSYLVANIA, ASSIGNOR TO THE ENTERPRISE MANUFACTURING COMPANY OF PENNSYLVANIA, OF PHILADELPHIA, PENNSYLVANIA, A CORPORATION OF PENNSYLVANIA.

CAN OPENER.

Application filed May 16, 1925. Serial No. 30,721.

My invention relates to certain improvements in can openers of the type having a feed wheel and a pivoted cutting blade.

- One object of the invention is to improve 5 the construction of a can opener of the above mentioned type by providing it with a handle and to design the cutting blade so that it can be held in contact with the can by the thumb of the hand holding the opener.
- 10 10 A further object of the invention is to design the can opener so that it will act as a handle for the can after the top is removed so that the contents can be poured from the can, or the can moved, as desired.
- 15 15 A still further object of the invention is to provide means whereby the cutting blade can be automatically brought into cutting position, on turning the feed wheel.

In the accompanying drawings:—
20 20 Fig. 1 is a side view of the improved can opener;

Fig. 2 is a plan view;

Fig. 3 is a side view of the can opener with the cutting blade in cutting position;

25 25 Fig. 4 is an enlarged sectional view on the line 4—4, Fig. 3;

Fig. 5 is a view illustrating a can with the top removed and the can opener acting as a handle for the can;

30 30 Fig. 6 is a side view showing the cutting blade geared to the shaft of the traction wheel, the blade being in the raised position; and

Fig. 7 is a rear view of the opener showing 35 35 the blade in the cutting position and its gear segment out of mesh with the gear on the shaft of the traction wheel.

The frame 1 of the can opener is made of sheet metal, which is cut and shaped as 40 40 shown in Figs. 1 and 2. The handle 2 is shaped so that it can be readily grasped by the hand of a person opening a can. The traction wheel 3 is toothed and forms an integral portion of a shaft 4, which has its 45 45 bearings in the frame 1, and is provided at the back of the frame with a handle 5 by which the traction wheel is turned.

Bent from the frame 1 are upper guides 6 and 7. Directly below the traction wheel 50 50 is a guide 8, which rests against the side of a can, as illustrated in Fig. 4, causing the frame to assume the proper angle when cutting, and insuring the contact of the traction wheel with the under side of the rim 9 of

the can 9. The guides 6 and 7 rest on the 55 upper edge of the can, as illustrated in Fig. 4.

Pivoted to the frame 1 is a cutting blade 9, which has a shearing edge 10, and provided with a point 11, which punctures a can prior 60 to the cutting thereof by the shearing edge 10 of the blade. The blade 9 has an extended portion 18, which forms a handle. On this portion is a lateral projection 12, which forms a thumb rest.

The forward guide 6 acts as a stop for the blade, when the blade is in the cutting position, as shown in Fig. 3. The cutting blade is mounted on a pivot 13, which extends through an embossed portion 14 of the frame 1. The face of the embossed portion is at a slight angle in respect to the plane of the traction wheel. The object of this construction is to retain the traction wheel in engagement with the flange of the can.

On referring to Fig. 5, it will be noticed that the rim of the can is held between the traction wheel and the blade so that, after the top has been removed by cutting, the can opener can be used as a handle in order 75 that the contents of the can can be readily poured.

The can opener can be easily detached from a can by raising the blade to the position shown in Fig. 1, clear of the rim of the can.

In Figs. 6 and 7 means is shown for automatically moving the blade into puncturing position during the primary movement of the traction wheel.

On the shaft 4^a of the traction wheel 3^a is a gear wheel 15, which has teeth that mesh with the teeth 16 of a segmental gear wheel 17, which is secured to the pivot 13^a of the cutting blade 9^a. The teeth of the segmental gear move out of mesh with the teeth of the gear wheel when the blade is moved to the cutting position. On reversing the shaft, and slightly raising the blade, the gear teeth of the segmental gear are 90 moved into mesh with the teeth of the gear wheel and the blade is raised clear of the wheel and the blade is raised clear of the rim of a can.

I claim:

1. The combination in a can opener, of a 105 frame; a traction wheel mounted on the frame and arranged to engage the underside of the rim of a can; and a cutting blade

- pivoted to the frame and arranged to cut the end out of a can, the blade having a point and cutting edge, said frame having a handle by which the opener is held as the can is rotated, the blade and the traction wheel holding the can at the rim so that the handled opener can be used as a handle for the can until it is released by raising the blade.
- 10 2. The combination in a can opener, of a frame having a handle; a traction wheel mounted on the frame and arranged to engage the rim of a can to be opened; a blade pivotally mounted on the frame, said blade having a point, a shearing portion and an extension forming a thumb rest; and lateral guides for the frame, one of said guides acting as a stop to limit the movement of the blade when in the shearing position.
- 15 3. The combination in a can opener, of a frame made of sheet metal and having a handle; two upper laterally extended guides formed integral with the frame and arranged to rest upon the rim of a can to be cut; a lower, integral guide arranged to rest against the side of a can; a traction wheel mounted on the frame and designed to engage the lower edge of the rim of a can; a cutting blade pivoted to the frame above the traction wheel, said blade having a point, a shearing edge and an extension, said extension being arranged to come in contact with one of the upper guides to limit the movement of the blade.
- 20 4. The combination in a can opener, of a frame made of sheet metal and having a handle; two upper laterally extended guides formed integral with the frame and arranged to rest upon the rim of a can to be cut; a lower, integral guide arranged to rest against the side of a can; a traction wheel mounted on the frame and designed to engage the lower edge of the rim of a can; a cutting blade pivoted to the frame above the traction wheel, said blade having a point, a shearing edge and an extension, said extension being arranged to come in contact with one of the upper guides to limit the movement of the blade; and gearing by which the blade is brought into contact with a can during the first movement of the traction wheel, the gearing being so formed that, when a can is being cut, the blade is disconnected from the traction wheel.

HARRY E. ASBURY.
